UNITED STATES PATENT OFFICE.

HEINRICH BAUER, OF FURTH, GERMANY.

STEEL-WIRE BRUSH FOR CLEANING THE TYPES ON TYPEWRITING MACHINES.

Application filed August 17, 1927, Serial No. 213,510, and in Germany September 23, 1926.

This invention relates to steel-wire-brushes for cleaning the types of typewriting-machines. With the improved brush a perfect cleaning of the types is easily and rapidly obtained in preserving the types, as the free ends of the steel-wires are softened to a hardness less than that of the types, these free ends being bent further at such an angle that, at the brushing, their points penetrate, owing to their resiliency, into the cavities of the types instead of slipping over the same as is the case with commonly used brushes.

An embodiment of the invention is shown, by way of example, in the accompanying drawings in which:

Fig. 1 shows in side elevation the improved brush as a flat brush.

Fig. 2 is a similar view, partly in longitudinal section.

Fig. 3 shows in cross section a semicircular brush.

Fig. 4 illustrates the effect of one single bent steel-wire in comparison with the straight bristle.

The steel-wires are fixed in a mounting *c* of suitable material embedded in the brush-head *d*. All the steel-wires are bent near their free ends at a uniform angle so that they form each a shank portion *a* and a cleaning finger *b*. The shank portions *a* are fixed in the mounting *c* and are hard and resilient, while the fingers *b* are resilient but relatively softer than the shank portions and than the metal of the type to be cleaned so that they will readily enter the type cavities and act therein without injury thereto. The brushes are normally in the position shown in Figs. 1, 2 and 3. When the brush is used by being moved over the type in the direction of the arrow-line (Fig. 1), the steel-wires yield slightly in backward direction so that the finger *b* stands approximately vertical, as shown in Fig. 4. The points of the fingers penetrate, under the action of the resilient shanks *a*, into the cavities of the type and remove all the dirt, while straight bristles slip over the cavities.

This effect is illustrated in Fig. 4. The bent steel-wire *a b*, fixed in the mounting *c*, tends to execute, at the brushing, an oscillating movement around the point of fixation *e*. The point of the wire moves therefore along an arc *f* which intersects the body *t* to be cleaned.

A straight bristle of steel-wire *g* indicated in Fig. 4 in mixed lines, oscillates around the point of fixation *h* and its point moves along an arc *i* which only touches the body *t* to be cleaned, and cannot penetrate into the cavities of the types. By thus "de-tempering" or making the tips or fingers of the brush bristles softer or of less resiliency than their shanks a two-fold effect is gained, firstly, the relatively softer and more flexible fingers slide into the cavities of the type and pick out the dirt therefrom, instead of springing over the cavities and riding on the surfaces of the type faces, as with bristles whose fingers are of the same degree of resiliency as their shanks, and, secondly, the use of softened tips prevents the rubbing wear and tear or scratching of the type faces occurring where bristles having hard fingers, or fingers of the same degree of resiliency as their shanks, are employed. I am thereby enabled to provide a type cleaning brush with metal bristles which will not only clean the surfaces but also the cavities of the type and is adapted to be repeatedly used without injury to the type.

The brush shown in Figs. 1 and 2 is designed for cleaning types of typewriting-machines situated in a plane. The semi-circular brush shown in Fig. 3 is designed for cleaning types arranged along an arc.

The brush-body may, however, be of any other shape.

The soft fingers of the steel-wires cannot damage the types and the tempered, resilient shanks *a* have not only the effect to press the soft points of the wires against the types, but also effect that the dirt in the cavities of the types is thrown out by the spring-action.

I claim:

A steel wire brush for use in cleaning the type of typewriting machines, comprising a brush head, and wire bristles mounted upon the head, said bristles having resilient shank portions fixed at one end to the head and provided at their opposite ends with angularly disposed cleaning fingers, said fingers being softer and of reduced resiliency with respect to the shank portions.

In testimony whereof I affix my signature.

HEINRICH BAUER,
